(57) **CLAIM**

The ornamental design for an infant feeding device, as shown and described.

DESCRIPTION

The patent or application file contains at least one drawing executed in color. Copies of this patent or patent application publication with color drawing(s) will be provided by the Office upon request and payment of the necessary fee.

Fig. 1.1 is a front view of a first embodiment of an infant feeding device.

Fig. 1.2 is a rear view of Fig. 1.1

Fig. 1.3 is a left view of Fig. 1.1

Fig. 1.4 is a right view of Fig. 1.1

Fig. 1.5 is a top view of Fig. 1.1

Fig. 1.6 is a bottom view of Fig. 1.1

Fig. 1.7 is a perspective view of Fig. 1.1

Fig. 2.1 is a front view of a second embodiment of an infant feeding device.

Fig. 2.2 is a rear view of Fig. 2.1

Fig. 2.3 is a left view of Fig. 2.1

Fig. 2.4 is a right view of Fig. 2.1

Fig. 2.5 is a top view of Fig. 2.1

Fig. 2.6 is a bottom view of Fig. 2.1

Fig. 2.7 is a perspective view of Fig. 2.1
